UNITED STATES PATENT OFFICE.

WILLIAM J. FLEEMAN, OF ST. JOSEPH, MISSOURI.

BURIAL CASKET.

Application filed June 19, 1926. Serial No. 117,083.

This invention relates to burial caskets and has for its object to provide in a manner as hereinafter set forth, a metallic burial casket possessed of lightness and durability and including a body portion provided with an inner and an outer lid or closure and with means associated with the inner lid or closure for hermetically enclosing a corpse and for effectively excluding moisture from 10 the interior of the body portion.

A further object of the invention is to provide, in a manner as hereinafter set forth, a metallic burial casket including an inner transparent closure or lid for the body portion and with means associated with said closure or lid to provide for the interior of the body portion to be absolutely air tight, resulting in the preservation of the corpse.

Further objects of the invention are to provide in a manner as hereinafter set forth, a metallic casket which is simple in its construction and arrangement, strong, durable, comparatively light in weight, air tight, waterproof, thoroughly efficient when used, and comparatively inexpensive to manufacture.

With the foregoing and other objects in view, the invention consists of the novel construction, combination and arrangement 30 of parts, as hereinafter more specifically described and illustrated in the accompanying drawings, wherein is shown an embodiment of the invention, but it is to be understood that changes, variations and modifications can be resorted to which fall within 35 the scope of the claims hereunto appended.

In the drawings wherein like reference characters denote corresponding parts throughout the several views:

Figure 1 is a top plan view of a metallic burial casket in accordance with this invention and with the outer lid raised and the inner lid in sealing position with respect to the body portion of the casket.

Figure 2 is a section on line 2-2 Figure 1 with the outer lid or closure in closed position with respect to the body portion of the casket.

Figure 3 is a fragmentary view, in vertical section upon an enlarged scale, of the casket.

Figure 4 is a sectional detail illustrating a modification of the structure of the body portion of the casket.

Figure 5 is a fragmentary view in trans-

verse section of a modified form of outer lid or closure.

A burial casket, in accordance with this invention comprises a composite body portion referred to generally by the reference character 1, an inner lid or closure referred to generally by the reference character 2, and an outer lid or closure referred to generally by the reference character 3. The body portion 1 is formed of an inner and 60 an outer metallic casing arranged in spaced relation and having interposed therebetween a non-metallic insert. Although the outer lid or closure 3 is formed of one piece of metallic material, yet it is to be understood 65 that the lid or closure 3 can be constructed in a manner similar to that referred to in connection with the body portion 1, that is to say the lid or closure 3 can be set up of an inner and an outer metallic section 70 and a non-metallic insert positioned between the sections.

The body portion 1 comprises an outer metallic section 4, an inner metallic section 5, a non-metallic insert 6 interposed 80 between the sides and ends of the sections 4, 5 and a non-metallic insert 7 interposed between the bottoms of the sections 4, 5. The sections 4 and 5 each is in the form of a casing of rectangular contour.

The section 4 is of greater height than the section 5. The bottom 8 of the section 4 projects laterally throughout with respect to the bottom 9 of the section 5, see Figure 2.

The side and end walls of the section 4, at the lower part thereof, are offset as at 10 and said offset portions terminate in the bottom 9 and seated on said bottom 8 and extending from the offset portions 10 is 95 the insert 7, which is co-extensive with the bottom 8. The insert 7 can be formed of any suitable non-metallic material, preferably wood. The inserts 6 are mounted upon the upper face of the insert 7 and said inserts 6 are constructed of the same material from which the inserts 7 are formed. The inserts 6 at their upper ends or rather have their top edges positioned below the top edge of the section 4 of the body portion 1.

The top edge of each of the inserts 6 is formed with a plurality of spaced pockets 11 of rectangular contour and which open at the inner sides of the insert, see Figure 3. 110

The inner wall of the pockets 11 terminate adjacent the outer face of the insert, see Figure 3. The purpose for which the pockets 11 are intended will be presently referred to.

The sides and ends of the section 5, at the upper ends thereof, are formed with right angularly disposed flanges 12 which are co-extensive with the top of the section 5 and said flanges 12 seat on the top edge of the insert 6 and further project outwardly with respect to these latter. The flanges 12 protect the top edges of the insert 6 and are formed with spaced openings 13 which register with the pockets 11.

The sides and ends of the section 4 at the upper part thereof, are offset as at 14, and then bent inwardly at right angles as at 15, and then downwardly at 16 and seat on the flanges 12. The downwardly extending portions 16 of the sides and ends of the section 4 are arranged in vertical alinement with respect to the portions of the sides and ends of the section 4 which are arranged below the lower end of the offset portions or parts 14. See Figure 2. The depending portions 16 form what may be termed continuations of the sides and ends of the section 4.

The depending portions 16 also form what may be termed abutments for the lid or closure 2 or in other words a confining means for the latter. The depending portion 16, in connection with the flanges 12, form what may be termed a rabbet on the inner side, at the upper end of the body portion 1. The portions of the flanges 12 which extend inwardly from the portions 16 of the section 1 provide a seat throughout the top of the body portion for an elastic gasket 17 which is co-extensive with the flanges 12. The gasket 17 is compressible and provided with openings 18 which register with the opening 13 formed in the flanges 12. The flanges 12 abut against the inner face of the offset portions 14, see Figures 2 and 3. The inwardly extending portion of each of the offsets 14 is provided with openings 19 having threaded walls and the function of the openings 19 will be presently referred to. The openings 19 are preferably formed in the inwardly extending portion 15 of the offset 14 formed at the upper end of the front wall of the section 4.

The inner lid or closure 2 consists of a frame 20 in which is secured a transparent panel 21 substantially of the same width and length of the section 5 of the body portion 1. The frame 20 is co-extensive with the gasket or packing 17 and is mounted thereon. The frame 20 is hinged as at 22 to the inwardly extending portion of the offset part 14 of the rear wall of the section 4. The frame 20 is formed with openings 23 which register with the openings 18 of the gasket, but the openings 23 are of less diameter than

the diameter of the openings 18. Mounted in each pocket 11, is the head 24 formed on the lower end of a socket forming member 25. The wall of the socket formed by the member 25 is threaded. The socket forming member 25 extends through the openings 13 and 18 but the height of the socket forming member 25 is such as to be positioned an appropriate distance below the lower face of the frame 20 to permit of compressing the gasket or packing 17 to set up an air tight seal between the inner lid or closure and the interior of the body portion 1. Extending through each of the openings 23 and having threaded engagement with the wall of the socket formed by the member 25 is a securing member 26 provided at its upper end with a head 27. The members 26 provide means for fixedly securing the lid or closure 2 in position to set up an air tight seal by compressing the gasket or packing 17.

The outer lid or cover 3 is constructed of metallic material is of semi-oval shape in cross section and provided with a laterally extending flange 28 which is co-extensive with the inwardly extending portions 15 of the offset parts 14 of the section 1. The flange 28 seats on the inwardly extending portions 15 and the flange 28 at its rear is hinged as at 29 to the offset portion 14 formed on the rear wall of the section 1 at the top thereof. The forward portion of the flange 28 is provided with openings 30 which register with the openings 19. Extending through the openings 30 and threadedly engaging with the walls of the opening 19 are securing devices 31 for fixedly maintaining the lid 3 in closed position.

Figure 4 illustrates the setting up of the sides and ends of the outer and inner sections of the body portion as formed of corrugated metallic material. In Figure 4 the outer section of the body portion is indicated at 32 and the inner section at 33. The non-metallic insert is designated at 34.

Figure 5 of the drawings illustrate the outer lid or closure 35 formed of an inner and an outer metallic section 36, 37 respectively, and an intermediate section 38 formed of non-metallic material. The shape of the lid or closure 35 is the same as the contour of the lid or closure 3 and is formed with an apertured flange 39 of the same arrangement as the flange 28. The lid or closure 35 is hinged and connected to the body portion, in the same manner as the lid or closure 3.

It is thought the many advantages of a metallic casket, in accordance with this invention can be readily understood, not only on account of its durability, but further for hermetically sealing the same to protect the corpse, and although the preferred embodiment of the invention is as illustrated and described, yet it is to be understood that changes in the details of construction can be

had which fall within the scope of the invention as claimed.

What I claim is:

1. A burial casket comprising a body portion formed of an outer and an inner section of metallic material and a non-metallic insert interposed throughout between said sections, said inner section provided at its top with an outwardly directed flange seated on the top of said insert and arranged below the top of said outer section, a compressible element mounted on said flange, a transparent inner closure for said body portion hinged at its rear to the top of said outer section, said closure seated on said element, interengaging means anchored against said insert by said flange and further extending through said closure, element and flange for fixedly securing said closure in air tight position, and an outer closure for said body portion.

2. A burial casket comprising a metallic body portion formed with a non-metallic insert, said body portion including means for overlapping the top edge of said insert, said means positioned below the top of said body portion, a transparent closure hinged at its rear to the top of said body portion, a compressible element seated on said means, said closure mounted on said element, inter-engaging securing devices anchored to said insert by said means, extending through the latter, said element and closure for fixedly securing the latter in air tight position with respect to said body portion, and a hinged outer closure for said body portion.

3. In a burial casket, a body portion comprising a metallic outer section in the form of a casing, a metallic inner section arranged within and spaced from the outer section and in the form of a casing, a non-metallic insert positioned between the sides, ends and bottoms of said sections and of less height than said outer section, said outer section having its upper part offset, said offset part formed with an inwardly extending angle-

shaped portion, said inner section having its top formed with an outwardly directed flange seating on the top of said insert and having said angle-shaped portion seated thereon, and means mounted on said flange and surrounded by said angle-shaped portion to provide an air tight transparent closure for said body portion.

4. A burial casket comprising a body portion formed of an inner metallic section, an outer metallic section and a non-metallic insert positioned between said sections and overlapped by said inner section, said sections having co-acting means at the top thereof to provide a continuous rabbet, a transparent inner closure mounted in said rabbet, a compressible element interposed between said closure and said inner section, and means anchored to said insert by said inner section and extending through said element and closure to fixedly secure the latter to the body portion to provide an air tight seal.

5. A burial casket comprising a body portion formed of an inner metallic section, an outer metallic section and a non-metallic insert positioned between said sections and overlapped by said inner section, said sections having co-acting means at the top thereof to provide a continuous rabbet, a transparent inner closure mounted in said rabbet, a compressible element interposed between said closure and said inner section, means anchored to said insert by said inner section and extending through said element and closure to fixedly secure the latter to the body portion to provide an air tight seal, means for hinging said closure to the outer section of said body portion, an outer closure hinged to said outer section and seating when in closure position upon said outer section, and means for securing said outer closure when in closed position to said outer section.

In testimony whereof, I affix my signature hereto.

WILLIAM J. FLEEMAN.
